US00D933714S

(12) **United States Design Patent** (10) **Patent No.:** **US D933,714 S**
(45) **Date of Patent:** **** Oct. 19, 2021**

(54) **METERING PUMP**

(71) Applicant: **MIXTRON S.R.L.**, Reggio Emilia (IT)

(72) Inventors: **Renato Brevini**, Reggio Emilia (IT);
Stefano Brevini, Reggio Emilia (IT)

(73) Assignee: **MIXTRON S.R.L.**, Reggio Emilia (IT)

(**) Term: **15 Years**

(21) Appl. No.: **29/694,930**

(22) Filed: **Jun. 14, 2019**

(30) **Foreign Application Priority Data**

May 30, 2019 (EM) 006547576

(57) **CLAIM**

The ornamental design for a metering pump, as shown and described.

DESCRIPTION

FIG. 1 is a perspective view of a metering pump according to the present design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the article shown in broken lines form no part of the claimed design.

1 Claim, 7 Drawing Sheets
